MANUFACTURE OF DIOLEFINS

Frederick E. Frey, Bartlesville, Okla., assignor to
 Phillips Petroleum Company, a corporation of
 Delaware

Application February 16, 1942, Serial No. 431,152

1 Claim. (Cl. 260—680)

1

This invention relates to the production of conjugated diolefins, and more specifically, to the utilization of amylenes as a source of diolefins.

Butadiene and related diolefins have been found in numerous instances among the products of low-pressure pyrolysis of various simple hydrocarbons, including both paraffins and olefins. In general, the diolefin yields reported in the literature are low. However, I have found as the result of numerous experiments, that enhanced yields of diolefins are obtained when the pyrolysis is conducted at a high temperature, with the time of heating limited to values small enough so that part of the hydrocarbon being pyrolyzed survives the heating unchanged. The yield of diolefins is further improved if the pyrolysis is conducted at low pressure or in the presence of diluents such as steam, flue-gas, methane and the like.

I have found that under suitable conditions of low pressure, high temperature and very short heating time good yields of diolefins containing four and five carbon atoms per molecule can be obtained from certain of the amylenes, namely, pentene-2 and trimethylethylene, while the yields are much lower from the other amylenes occurring in cracked material in appreciable amounts, i. e. unsymmetrical methylethylethylene and pentene-1.

The objects of my invention are:

1. To effect the pyrolytic conversion by a recycle process of suitable amylenes into useful and substantial yields of butadiene and pentadienes.

2. To utilize a hydrocarbon fraction containing five carbon atoms per molecule and containing a considerable proportion of amylenes such as the C₅ fraction obtained from typical cracking still gasoline.

3. To produce, by an economical separating means, a conversion feed stock rich in the preferred olefins and differing in olefin make-up from such a C₅ fraction.

4. To provide an advantageous combination of such separating means with conversion means for producing butadiene and pentadienes.

5. To produce aliphatic conjugated diolefins and other useful by-products.

6. To provide a new process of cracking pentene-2 and/or trimethylethylene to diolefins.

Numerous other objects will more fully appear hereinafter from a consideration of this description taken in conjunction with the accompanying drawings wherein:

Fig. 1 portrays diagrammatically one form of

2

equipment useful for carrying out the recovery of pentene-2 and trimethylethylene from an amylene-containing refinery C₅ fraction to be passed to the pyrolysis step.

5 Fig. 2 is a modification of Fig. 1 showing fractionation of the C₅ fraction before entering the solvent extraction unit.

Fig. 3 portrays diagrammatically one form of equipment for carrying out the pyrolysis of the 10 desired amylenes.

The economical and efficient production of aliphatic conjugated diolefins, in particular butadiene, piperylene and isoprene, which are raw materials for the production of synthetic rubber, 15 from readily available hydrocarbons of petroleum origin, is a serious problem, and one which has not to my knowledge been entirely satisfactorily solved. My invention seeks to provide a commercially feasible solution to this problem.

20 I use amylenes as the starting material for my process. Usually I take a refinery C₅ stream containing pentanes and pentenes, although it may comprise preponderantly or consist essentially of pentenes. Higher and lower paraffins 25 and olefins may also be present in the stream. I prefer to first treat this stream so as to eliminate such higher or lower paraffins or olefins, if present.

The fairly pure C₅ stream may be subjected to 30 catalytic isomerization to increase the concentration of pentene-2 and also trimethylethylene therein. This step converts pentene-1 largely to pentene-2 and also converts unsymmetrical amylene to trimethylethylene. Thus the concentration 35 of the desirable high boiling point amylenes is increased, at the expense of the undesirable low boiling point amylenes.

The isomerization step per se does not constitute 40 my invention. The details of effecting this isomerization are well understood by and will be obvious to those skilled in the art in the light of this disclosure taken in conjunction with the prior art.

Where the content of the desirable amylenes in 45 the available C₅ or pentene stream is sufficiently high to make solvent extraction thereof economically feasible, the isomerization step may be omitted, and the feed subjected to solvent extraction.

50 In some cases a feed is available which is sufficiently rich in the desired amylenes (pentene-2 and/or trimethylethylene) to use as cracking feed directly or after fractionation to remove C₃ and lighter and C₆ and heavier if present.

The isomerization effluent or, where isomeri-

zation is omitted, the substantially pure C₅ stream free from lighter and heavier hydrocarbons, may next be subjected to selective solvent extraction with a polar solvent capable of exerting a preferential solvent action upon olefins as distinguished from paraffins and upon the desirable higher-boiling amylenes (pentene-2 and/or trimethylethylene) as distinguished from the undesired low-boiling amylenes (pentene-1 and unsymmetrical amylene).

Upon stripping the separated polar solvent there is recovered a cracking feed concentrate rich in or consisting essentially of pentene-2 and/or trimethylethylene.

The isomerization step described above is desirable for several reasons. It lowers the overall cost of operating the process and of producing diolefins, makes a larger volume of the desirable amylenes available for cracking and lowers the unit cost of solvent extraction of the high-boiling amylenes because of their higher concentration in the feed to the extraction unit.

The cracking feed thus prepared is now subjected to cracking in such manner as to convert the pentene-2 and trimethylethylene content thereof largely to diolefins, especially butadiene and pentadiene. The dehydrogenation of trimethylethylene gives largely isoprene while the cracking of pentene-2 gives mainly butadiene and some piperylene. Some cyclopentadiene may also be frequently formed in the cracking step.

The cracking may be carried out at a temperature above 700° C. up to 900° C. and preferably from about 750° C. to about 850° C. The specific cracking conditions, i. e. time-temperature relationship, are indicated below. The pressure may range from about 0.1 to about 2 atmospheres but is preferably substantially atmospheric.

The cracking may advantageously be conducted in a two-step manner, as described in the co-pending application of H. J. Hepp, Ser. No. 431,175 filed of even date herewith, wherein the feed is first cracked under relatively mild conditions to selectively destroy pentene-2, and the butadiene is recovered from the effluent, the C₅ portion of the effluent being then cracked under more drastic conditions to convert the trimethylethylene content thereof to isoprene.

The cracking of pentene-2 specifically is not claimed herein but is claimed in my co-pending application Ser. No. 431,151, filed of even date herewith.

By means of the present invention, exceptional yields of desirable diolefins are obtainable. The cracking conditions contribute largely to these high yields. Also the combination, cooperation, and inter-relation of the several steps of obtaining the concentrate rich in pentene-2 and/or trimethylethylene which is especially suited for cracking to the desirable diolefins, contribute very materially to the high yields of desirable diolefins based on the original amylene-containing raw material.

The diolefins comprise largely butadiene and pentadienes. The pentadienes comprise mainly isoprene, some piperylene depending on cracking conditions, and some cyclopentadiene which is undesirable. Pentene-2 gives mainly butadiene, some piperylene and perhaps some isoprene. Trimethylethylene gives mainly isoprene, some butadiene, and occasionally some piperylene. The overall yields of diolefins based on pentene-2 and/or trimethylethylene charged to the cracking unit may run as high as from about 35% to

about 45%. These are materially higher than the yields obtainable with any prior art process of cracking these pentenes, with which I am familiar.

A charge stock which comprises a hydrocarbon fraction containing five carbon atoms per molecule and containing a considerable proportion of amylenes, such as the C₅-fraction obtained from typical cracking-still gasoline, enters the system 10 through pipe 1, controlled by valve 2, and passes to a debutanizer 3. The C₄-hydrocarbons and lighter products are recovered overhead and are withdrawn from the system through pipe 4 and valve 5. The hydrocarbons which are higher 15 boiling than the C₄-hydrocarbons are recovered as kettle product and are passed through pipe 6, controlled by valve 7, to depentanizer 8. The C₅-hydrocarbons and heavier products are recovered as kettle product and removed from the 20 system through pipe 9, controlled by valve 10. The C₅-hydrocarbons are recovered overhead and are passed through pipe 11, by means of valves 12 and 13 to solvent extraction unit 14.

If desired, a portion or all of the C₅-hydrocarbons 25 may be passed, controlled by valve 13, from pipe 11 through pipe 15, by means of valve 16 to an isomerization step. The purpose of this isomerization step is to effect conversion of pentene-1 to pentene-2. By means of heating arrangement 17, the stream is heated to a temperature in the range of from about 150° to about 350° C. and passed to isomerization step 18. The stream is there contacted with a suitable catalyst such as phosphoric acid, aluminum sulfate, or the like, for a period of time, in the range of from about 2 seconds to about 3 minutes, sufficient to effect substantial isomerization of pentene-1 to pentene-2; there will be some conversion of unsymmetrical amylene to trimethylethylene.

A typical refinery C₅-fraction, such as that being charged to the isomerization step, would have about the following composition: pentene-1, 9%; pentene-2, 17%; trimethylethylene, 9%; unsymmetrical methylethylene, 5%; and the remainder predominantly pentanes. An isomerizer 45 would effect such conversion that the ratio of pentene-1 to pentene-2 in the isomerization effluent would be about 1 to 10.

The effluents from the isomerization step are 50 passed through pipe 19, controlled by valve 20, to a fractionating step 21. The C₅-hydrocarbons and heavier products are separated as kettle product and withdrawn from the system through pipe 23, controlled by valve 24. Pentane-pentenes and any lighter hydrocarbons present are passed through cooler 22, which supplies a liquid condensate for reflux in column 21, pipe 26, valve 27 to pipe 11, to be subjected to further separation 55 steps.

The C₅-hydrocarbon fraction is next subjected 60 to separation means in order to obtain concentrates of pentene-2 and/or trimethylethylene. As shown in Figure 1, separation may be effected by means of solvent extraction; the solvent extraction step may however, be preceded by a fractionation step, as shown in Figure 2. In an alternative method trimethylethylene and cis- and trans-pentene-2 may be separated from other pentanes 65 and non-cyclic olefins present by means of azeotropic distillation employing acetaldehyde, propionaldehyde or other suitable materials as entrainers. This azeotropic fractionation may be preceded by a simple fractionation to separate 70 low-boiling pentane and pentenes, i. e. boiling be-

low about 35° C. While this particular combination is not shown in the figures, the manner of conducting such distillations, and the equipment required, will be readily apparent to one skilled in the art. Vapor-phase extraction with a liquid solvent is preferred.

When extracted without previous treatment or separation, the C₅-hydrocarbon fraction is passed from pipe 11 to solvent extraction tower 14. Solvent, which may be any convenient selective solvent such as furfural is introduced into the extraction tower through pipe 28, and heating of the contents of the tower is effected by means of a heating coil 29. It may be necessary, in order to decrease or prevent loss of solvent overhead, to maintain "reflux" in the upper portion of the tower by a cooling coil or by recycling a portion of the effluent, which has been cooled by suitable means, to the upper portion of the tower. The extraction, in the case of furfural, is effected at temperatures in the range of from about 50 to about 350° F., preferably in the range of from about 125 to about 225° F., and at pressures such that, at the temperatures prevailing, the vapor does not reach its dew-point. The temperature is not necessarily constant over the whole column, and the lowest temperature ordinarily should be such that dew-point conditions do not exist under the prevailing temperature and pressure conditions.

The fraction recovered overhead is composed predominantly of the pentanes, pentene-1, 2-methylbutene-1 (unsymmetrical methylethylene), and 3-methylbutene-1. The components which are desired as feed for a cracking step, to be described later, are recovered along with the solvent as kettle product, and this mixture is passed through pipe 32, controlled by valve 33, to stripping tower 34. Heat is supplied to the tower by means of a heating coil 35, and the stripped solvent is recovered as kettle product and passed through pipe 36, being withdrawn if desired through valve 37 but usually being passed to a cooler 38, wherein the stream is cooled to a desired temperature and recycled to the solvent extraction step with fresh solvent through pipe 28. Pentene-2 and trimethylethylene are recovered overhead in concentrated form and are passed through pipe 39, controlled by valve 40, to the cracking unit shown in Figure 3.

When it is desirable to effect a preliminary separation before subjecting the C₅-fraction in line 11 to solvent extraction or azeotropic distillation, fractionation in a column of the conventional type is employed. The C₅-hydrocarbon fraction is passed, as shown in Figure 2, through pipe 11 to the fractionator 41, wherein the hydrocarbons are split into a low-boiling group and a high-boiling group. The cut-point for this operation, if made at about atmospheric pressure, should be in the range of 32 to 36° C., preferably about 34° C. Isopentane, pentene-1, 2-methylbutene-1 and 3-methylbutene-1 are recovered overhead and withdrawn from the system through pipe 42, by means of valve 43.¹ Normal pentane, pentene-2, and trimethylethylene are recovered as kettle product and passed through pipe 44, controlled by valve 45, to a solvent extraction tower 46. Solvent extraction is effected herein as described in the previous case, solvent being supplied through pipe 47 and heating being effected by means of heating coil 48.

Normal pentane is recovered overhead and withdrawn from the system through pipe 49, by means of valve 50. The solvent extract, containing pentene-2 and trimethylethylene, is passed from the bottom of the tower through pipe 51, controlled by valve 52, to stripping tower 53, which is heated by coil 54. The stripped solvent is recovered as kettle product and is passed through pipe 55, controlled by valve 56, through cooler 57 and recycled through pipe 47 to the solvent extraction tower. Pentene-2 and trimethylethylene are recovered overhead and passed through pipe 58, controlled by valve 59, to the cracking unit shown in Figure 3.

The cracking system as shown in Figure 3 will now be described. The pentene-2 and/or trimethylethylene concentrate from pipe 39 or from pipe 58 is passed to a heating system, which is herein represented by a convection coil, 60, and a radiation coil, 61. Steam or other stable, volatile diluent may be added to the charge stock; from pipe 62, steam etc., may pass through valve 63 directly to the convection coil 60 of the furnace or it may pass from pipe 62 through pipe 64, controlled by valve 65, to a separate heating coil, 66, and thence through pipe 67, by means of valve 68, to the convection coil 60 of the furnace or from pipe 61 through pipe 69, controlled by valve 70 to a radiation coil of the furnace. The charge stock is cracked in the furnace at temperatures above 700° C. up to 900 C., and preferably from about 750° C. to about 850° C. The heating time varies inversely with the temperature, decreasing as the temperature rises, and is adjusted to effect from about 30 to about 80 per cent decomposition of the less refractory pentene-2 per pass through the heating zone. The decomposition should be maintained in the lower part of the range when no diluent is used, or when the partial pressure of the amylanes is near or slightly above atmospheric pressure. The higher conversion may be employed when the pyrolysis is conducted at pressures below atmospheric, or when diluents such as steam are employed.

The effluents from the cracking step are passed from the furnace through pipe 71, by means of valve 72, to cooler 73; the cooled effluents are passed to separation step 74. Polymers and water from the cracking step are withdrawn from the bottom of the separating column through pipe 75 by means of valve 76. The gases pass overhead through pipe 77, controlled by valve 78, to compressor 79, through pipe 80 to cooler 81 and through pipe 82 to separator 83. From the separator, gases pass overhead through pipe 84, controlled by valve 85, to a depropanizing column 90; the liquid products in the separator pass from the bottom of the column through pipe 86, controlled by valve 87, to pipe 88 and join the stream 60 of any liquid products from separation step 74 which are being passed through pipe 88, controlled by valve 89 and pump 87a' to the depropanizer. From the depropanizer, which is of the conventional type, propane and lighter gases are separated overhead and are withdrawn from the system through pipe 91, controlled by valve 92. Other means equivalent in function to elements 74, 83, and 90 may be used, if desired.

The kettle product from the depropanizer 90 passes through pipe 93, controlled by valve 94, to a debutanizer, 95. In this unit, the C₄-hydrocarbons are recovered as overhead product and are passed through pipe 96, controlled by valve 97, to a purification step 98. The C₄ fraction will 75 be composed predominantly of butadiene, and

¹This stream or a portion of it may be returned to the isomerization step if desired by means not shown.

the butadiene may be separated from the other hydrocarbons by formation of the sulfone by reaction in unit 98 with SO_2 introduced via line 96A. The butadiene sulfone is withdrawn from the system through pipe 99, by means of valve 100, and the remaining C_4 -hydrocarbons pass from the purification step through pipe 101 to be recycled to the cracking step through valve 102 and pipes 39 or 58 or withdrawn from the system through pipe 103, controlled by valve 104.

The kettle product from debutanizer 95 is withdrawn and passed through pipe 105, by means of valve 106, to depentanizer 107. The kettle product from this unit is withdrawn from the system through pipe 108 by means of valve 109. The C_5 -hydrocarbons pass overhead through pipe 110, controlled by valve 113, and are subjected to a purification unit 114, such as sulfone formation, to separate the diolefins. SO_2 may be introduced to unit 114 via line 112. Pentadiene sulfones are withdrawn through pipe 115, by means of valve 116, and the unreacted C_5 -hydrocarbons are passed overhead through pipe 117 and, through valve 118, recycled to the cracking step.

In the process described in connection with Figure 3, the diolefins are recovered by reacting with sulfur dioxide. The monosulfone thereby formed may be separated from the unreacted products by decantation and/or distillation, and the diolefin regenerated by heating the monosulfone to temperatures above about 80° C . and preferably above about 120° C . The reaction between diolefins and sulfur dioxide may suitably be conducted in the dense phase at temperatures in the range of from about 30° to about 180° C , and preferably in the range of from about 100 to about 150° C . Inhibitors such as pyrogallol, phenyl-beta-naphthylamine, etc., may be employed in the low temperature range to avoid the formation of insoluble, refractory polysulfones which do not regenerate the diolefin readily, but inhibitors are not necessary at temperatures above about 100° C . as polysulfones are formed only in small amount, if at all, at these temperatures. The time required to complete the sulfone reaction varies inversely with the temperature, from several days at 30° C . to about one-half to two hours at 150° C . The amount of sulfur dioxide used may be in the range of from about 2 to about 20 moles per mole of diolefin. The reaction is kinetically of the second order, and the time required is decreased as the amount of sulfur dioxide is increased.

While I have shown separate diolefin recovery systems on both the butadiene- and pentadiene-containing streams, these steps may be combined, the butadiene and pentadiene sulfones being recovered together. Upon regeneration butadiene may be readily separated from pentadienes if desired by fractionation.

Other methods of recovery of butadiene and pentadienes may be used if desired. In alternative methods of recovering diolefins and recycle stocks to those shown in Figure 3, butadiene may be recovered from the C_4 -hydrocarbons passing through pipe 96 by fractional distillation, wherein butene-1 and isobutylene are separated in a first fractionator, following which butadiene is separated from butene-2. Or the separation may be performed in a single step using an entrainer such as acetaldehyde. Or another method of separation is by means of selective solvent extraction, using for example, furfural as the solvent.

The recovered butenes may be returned to the pyrolysis step.

Similarly, fractionation, solvent extraction or azeotropic distillation may be employed in addition to the sulfone process described in Figure 3 to recover isoprene and piperylene from the stream flowing through pipe 110.

The following examples are cited for purposes of illustration only to show about the yield of products obtained from pentene-2 and trimethylethylene when pyrolysed under conditions as disclosed in my invention.

Products of pyrolysis of pentenes

		Example No.

¹ Difference in total and 100.0 is the CO and CO_2 found in the effluent gas.

The cracking conditions used may be governed by the following considerations.

In the case of a feed to the cracking unit consisting essentially of or comprising largely pentene-2, the time-temperature relationship to obtain from 20 to 70 per cent cracking per pass is determined by the following Equation 1.

$$(1) \quad \log t = \frac{13,900}{T} - (14.85 \pm 0.37)$$

where t is reaction time in seconds and T is cracking temperature in degrees Kelvin.

Pentene-2 may be cracked unusually extensively without excessive loss in butadiene yield. Laboratory data showed a C_4H_8 yield of 25.6 wt. per cent at 73% of the pentene cracked. This yield increased only to 34.1% at 36 per cent reacted. It may be sometimes desirable, particularly when mixtures of pentene-2 and trimethylethylene are cracked in two steps, to use the deep conversion.

When dealing with a feed to the cracking unit comprising mainly or consisting essentially of trimethylethylene, the most useful range is 15 to 50% converted per pass. The following Equation 2 covers the time-temperature relationship covering this region:

$$(2) \quad \log t = \frac{13,350}{T} - (13.65 \pm 0.31)$$

75 The exact amount of decomposition selected

depends upon the presence or absence of diluents. With diluents, a higher decomposition per pass may be usually employed without loss of efficiency. The amount of decomposition also depends upon the temperature used. Thus, in the lower temperature range, the extent of decomposition per pass will usually be maintained in the lower portion of the range of per cent cracked.

When dealing with mixtures of pentene-2 and trimethylethylene, the cracking conditions selected will depend upon the proportions thereof in the feed to the cracking unit or units. If the feed to the unit (including any recycle) predominates, i. e. contains more than 50%, in pentene-2, then conditions for that unit will be selected in accordance with Equation 1 above for pentene-2. If it predominates in trimethylethylene, conditions selected in accordance with Equation 2 will be used. For mixtures, I may use two stage cracking as described in the above-identified co-pending application of H. J. Hepp.

Since the invention may be practiced otherwise

than as specifically described herein, and since various modifications and variations of it will be obvious to those skilled in the art, it should not be restricted except as specified in the appended claim.

5 I claim:

The process for the production of isoprene from trimethylethylene which comprises subjecting a feed stock comprising trimethylethylene to pyrolysis in a reaction zone at a temperature within the range of 750 to 850° C. at substantially atmospheric pressure for a period of time within the limits of the following equation:

$$15 \log t = \frac{13,350}{T} - (13.65 \pm 0.31)$$

10 where t is the reaction time in seconds and T is the temperature in degrees Kelvin, whereby from 15 to 50 per cent of the trimethylethylene content of the feed is reacted with the production 20 of isoprene.

FREDERICK E. FREY.
